UNITED STATES PATENT OFFICE.

CHARLES V. STRICKLAND, OF WINSTON-SALEM, NORTH CAROLINA, ASSIGNOR TO R. J. REYNOLDS TOBACCO COMPANY, OF WINSTON-SALEM, NORTH CAROLINA, A CORPORATION OF NEW JERSEY.

CAN-BOTTOMING MACHINE.

1,413,240.

Specification of Letters Patent. Patented Apr. 18, 1922.

Application filed June 28, 1919. Serial No. 307,372.

To all whom it may concern:

Be it known that I, CHARLES V. STRICKLAND, of Winston-Salem, in the county of Forsyth and State of North Carolina, have invented certain new and useful Improvements in Can-Bottoming Machines, of which the following is a specification:

The present invention relates to a machine for fitting can bottoms upon can bodies and is especially adapted to handle such cans as have a flat-sided round ended can body and a can bottom having a flat sided round ended recess of similar contour, the side walls of said recess being inclined. Cans of this character at the present time are largely used for packing tobacco.

In accordance with the present invention the can body is held in position on a bed by a movable clamp and a can bottom carried by a movable feeder is moved toward the open end of the clamped can body and the recessed portion of the can bottom is forced into the can body, being wedged tightly therein. The can body clamp and the can bottom feeder are moved in cooperative sequence from a common actuator.

The particular machine herein set forth is so organized that the can bodies are fed by one hand of the workman onto the bed beneath the can body clamp while the can bottoms are fed by the other hand of the workman to the can bottom feeder, and the actuator for the clamp and feeder is moved by one foot of the workman. With this machine a single workman can fit together can bodies and bottoms of a large number of cans with ease and rapidity.

The improved machine is provided with feed tables for the can bodies and can bottoms and the can body feed table is equipped with guides to insure the accurate placement of the can bodies in position beneath the can body clamp.

A machine embodying the present improvements is illustrated in the accompanying drawings, wherein—

Figure 1 is a feed side view of the machine, parts being broken away to facilitate illustration. Fig. 2 is a discharge side view of the can body clamp, the can bottom feeder and the parts immediately associated therewith. Fig. 3 is a plan view of the machine. Fig. 4 is a cross section in the plane

indicated by the line 4—4 in Fig. 1, and illustrates the can bottom feeder. Fig. 5 is a cross section in the plane indicated by the line 5—5 in Fig. 3. Fig. 6 is a cross section in the plane indicated by the line 6—6 in Fig. 3. Fig. 7 is a face view of the can bottom feeder. Fig. 8 is a plan view of such a can bottom as is handled by the machine. Fig. 9 illustrates a can bottom fitted into a can body. Fig. 10 is a partial longitudinal section in the plane indicated by the line 10—10 in Fig. 3. Fig. 11 is a detail view of the actuating pedal. Fig. 12 is a diagrammatic side view partially in vertical section illustrating the mode of operation.

Figs. 4 to 10 inclusive are on a larger scale than Figs. 1 to 3 and Fig. 11. Fig. 12 is on a still different scale larger than that of Figs. 1 to 3, but smaller than the scale of Figs. 4 to 10.

A flat sided can body X such as is indicated in Figs. 5, 6 and 10 is placed by hand upon a bed H (Figs. 6 and 10) with one of its flat sides resting upon the horizontal surface of the bed. At its rear end the bed has a vertical abutment I extending upwardly at right angles to the surface of the bed and the can body is inserted so that its rear open end (constituting its top or mouth) is alongside the abutment as illustrated in Fig. 10.

Cooperating with the bed is the can body clamp G. This can body clamp is a weighted head which normally occupies its uplifted position shown in Figs. 1, 2, 5 and 6. In this position it is held upwardly away from the bed sufficiently far to enable a can body to be readily inserted flat-wise upon the bed and below the clamp as indicated in Figs. 5 and 6.

At the front of the bed plate H is located the movable can bottom feeder M, shown best in Figs. 4, 7, 10 and 12. A can bottom is placed by the other hand of the workman upon the feeder when the feeder occupies its normal position shown in Fig. 1.

The workman thereupon moves the common actuator A for the can body clamp and the can bottom feeder. The actuator is, as shown, a foot controlled pedal and it is operatively connected both with the clamp and with the feeder. When the actuator is

5 moved by the workman, the clamp lowers to the position shown in Fig. 10, thereby clamping the can body upon the bed and positioning and confining the can body so that 10 its outer open end is accurately placed for the reception of the can body. Also the can bottom feeder is moved toward the can body thereby wedging the recessed portion of the can bottom into the open end of the can 15 body, thus fitting and uniting the two together.

10 The operative connections between the actuator and the clamp and feeder are such that, although at the start both clamp and 15 feeder move concurrently toward the can body, the clamp is at rest before the can bottom feeder brings the can bottom into contact with the can, and the can bottom feeder completes its feeding movement after the 20 clamp is at rest. Fig. 10 shows the intermediate stage in the movement of the actuator, at which the clamp has descended completely and is at rest while the feeder is still 25 only about half way through its feeding movement. Fig. 12 illustrates in full lines this intermediate stage, and in dotted lines the positions which the can bottom feeder and for the clamp occupy at the completion of 30 the feeding stroke of the can bottom feeder.

35 The uniting action being completed the workman releases his foot pressure on the actuating pedal, and a spring 5 restores the clamp, the feeder and their actuating mechanism to their normal idle positions of rest illustrated in Fig. 1. The bottomed can body is then removed and the machine is ready to act upon the can body and can bottom of the next can.

40 In the following detailed description of the mechanism, there will be described in the following order, the bed, the clamp, the feeder, the actuating mechanism for the clamp and feeder, the feed table for the can bodies, and the feed table for the can bottoms.

45 *Can body bed.*—The bed H which receives the can body resting on one of its flat sides has an upper horizontal surface of the width and length of the can body. At its inner end it is recessed at j so as to accommodate the usual projecting rib or bead i near the top end of the can body. The bed has an upward projection k , at its rear end (Fig. 10) 50 which serves as a stop to limit the downward clamping movement of the clamp G. Also, to this projection is fastened the vertical thrust abutment I for the inner end of the can body. This thrust abutment extends vertically and at right angles to the bed. Preferably it is a hardened steel plate separate from the stop projection k and secured thereto by screws as shown in Figs. 5, 6 and 10.

55 *Can body clamp.*—The clamp G is a weighted head sufficiently massive so that

when it is down, the can body will be prevented from buckling or from moving vertically as the can bottom is fitted therein. The clamp G overlies the bed and it has a rearward extension g pivoted at h to the frame 1 70 of the machine. The clamp moves vertically with respect to the bed, swinging on the pivot h . The clamp is guided in its up and down movements by side guides K which are secured at opposite sides to the clamp 75 and which extend downwardly alongside the stop projection k , of the bed. The clamp has a downwardly projecting foot l (Fig. 10) which is back of the thrust abutment I and immediately over the stop k with which 80 it comes in contact when the clamp lowers thereby limiting the downward movement of the clamp and bringing the clamp at rest in the proper position relatively to the bed to position and confine the can body in 85 proper bottom receiving position.

90 The clamp has on its lower face a downwardly projecting crosswise extending rib m which bears upon the middle of the upper side of the can body when the clamp is in its lower position of rest, as indicated in Fig. 10. The upper side of the can body is thus maintained parallel with the lower side at the desired distance therefrom so that both flat sides of the can are maintained in proper 95 position to receive the can bottom. At its forward end the clamp has a downwardly projecting flange n the bottom edge of which is shaped to conform to the contour of the upper half of the can body as it rests upon 100 the bed, as indicated in Fig. 5. This flange acts as the clamp descends to center the front end of the can. Also, the depending side legs of this flange fit the rounded ends 105 of the can body down to the middle of the can as it rests on the bed plate, thereby preventing any sidewise movement of the front end of the can body on the bed. Also, the horizontal lower edge of the flange rests upon the top side of the can body, thus aiding 110 the rib m in maintaining the upper side of the can body in proper can bottom receiving position. Accordingly, the outer open 115 end of the can is clamped accurately in place ready for the reception of the can body. On its inlet or feeding side near the rib m the clamp has fastened to it a downwardly projecting guide and retaining finger p which, as the clamp descends, centers and positions the rear end of the can body. 120

125 On the opposite or discharge side, the clamp has pivoted to it a swinging door J (Fig. 2) which is maintained by a spring o in its normal depending position, shown in full lines. When the door occupies this normal position it serves as an adequate stop to limit the infeed movement of a can body and also aids in centering the can body as the clamp descends. This spring controlled door can swing outwardly to the position 130

shown in dotted lines in Fig. 6 to permit the discharge of a bottomed can at the exit side of the bed.

Can bottom feeder.—The feeder M is pivoted at *r* to the frame 1 of the machine, as shown in Fig. 4, immediately in front of the bed. The feeder has a die or "stake" L projecting from its upper face which conforms in shape to the interior of the recess in the can bottom, and has inclined edges conforming to the inclination of the walls of the recess of the can bottom. The can bottom is placed by hand with its recess fitting over this die. The bottom is thus held in position during the swinging feeding motion of the feeder toward the open end of the can body. To facilitate placing the can bottom by hand accurately upon the die the feeder has upwardly projecting outer ends *g* as shown in Figs. 4 and 7. These outer ends *g* flare upwardly so that at their free edges they are farther apart than where they join the body of the feeder; and they also converge from the upper to the lower edge of the feeder, as indicated in Fig. 7, thereby providing a flaring mouth for the ready entrance of the can body and a guide to direct the incoming can bottom into central position to fit over the die L.

30 The feeder swings from the normal idle position of rest shown in Fig. 1 (in which position it is at an angle of about 45° to the horizontal) to the vertical position shown in dotted lines in Fig. 12 where it is parallel with the open front end of the can body and is as close thereto as the thickness of the metal of the can bottom flange permits.

Actuating mechanism.—The clamp G is lowered and the feeder is moved toward the clamped can body by movement of the actuator A. The actuator is a pedal pivoted at *a* to the frame 1 and near its lower end it has a foot stirrup *b* (Figs. 1 and 11) so that it may be moved by the foot of the workman. This actuator A is operatively connected with the can bottom feeder and with the can body clamp so that both at the outset move concurrently, but the downward movement 50 of the clamp ceases before the feeder brings any portion of the can bottom into contact with the can body. Accordingly, the can body is centered and positioned, confined and clamped before the can bottom is brought 55 into initial engagement therewith.

The actuator A at its upper end has a forwardly extending toggle arm B the rear end of which is connected by a toggle link C to the feeder. The pivotal connection between 60 this toggle link and feeder is shown at *s* in Fig. 1. The toggle is normally broken, as shown in Fig. 1. When the lower end of the actuating pedal is swung rearwardly (to the right in Fig. 1) by the foot of the 65 workman, the toggle arm B is lifted thereby

swinging the can bottom feeder upwardly and finally to vertical position as indicated by dotted lines in Fig. 12. The feeding movement of the feeder continues throughout the rearward swing of the actuating 70 pedal. At the end of this swing, the toggle straightens thereby giving adequate power to force the recessed section of the can bottom into the open end of the can body.

The actuating pedal is so connected to the can body clamp that the pedal and the intermediate connections can continue to move after the clamp lowers to its position of clamping rest. A bell crank lever is pivoted at *e* to the frame 1. Its upper horizontal arm F extends forwardly beneath the clamp and the forward end of said arm is immediately beneath the head of a vertically adjustable screw stud *f* carried by the clamp. As shown in Fig. 1, the clamp is normally 80 upheld by reason of this stud resting upon the free forward end of the lever arm F, which serves as a support therefor.

The lower vertical arm E of the bell crank lever is connected by a forwardly extending link D to the pedal A. As shown in Fig. 1, this link D is pivoted at *c* to the pedal and at *d* to the lower arm E of the bell crank lever. As the actuating pedal is swung rearwardly the arm F of the bell 90 crank lever swings downwardly and the clamp correspondingly lowers by gravity following the downward movement of the lever arm F. This concurrent downward movement continues until the position is reached 95 which is shown in Fig. 10 and in full lines in Fig. 12. At this stage the downward movement of the clamp ceases because its foot *l* contacts with the stop *k*. At this instant the can bottom feeder has been moved only 100 about half way from its idle position shown in Fig. 1 to its can bottom applying position, shown in dotted lines in Fig. 12. This intermediate position is that which is shown in full lines in Fig. 12. During the further rearward movement of the pedal necessary to complete the feeding movement of the can bottom feeder, the bell crank lever E, F, swings away free of the can body clamp to the position shown in dotted lines 110 in Fig. 12. This is permitted because the connection between the lever arm and the clamp through the stud *f* is, in effect, a lost motion connection, permitting the bell crank lever to continue to swing after the clamp is 115 at rest.

If the can body has not been seated against the thrust abutment I by the workman, the can bottom feeder acts upon the outer end of the can body and slides it to the rear until it has firmly seated against the abutment I. After this seating occurs the further feeding movement of the feeder wedges the can bottom into the can body. The union between can body and can bottom 130

having been thus effected the workman releases the actuating pedal, and the spring 5 restores the actuating mechanism, the clamp, and the feeder to their normal positions shown in Fig. 1. This normal position is determined by a fixed stop 4 against which the arm E of the bell crank lever is brought by the action of the spring 5, as shown in Fig. 1.

- 10 *Can body feed table.*—Mounted upon brackets 3 of the frame 1 at the feed side of the bed and clamp is the can body feed table 2, the upper surface of which is flush with the upper surface of the bed H. This 15 feed table has upwardly extending inclined spaced guides 6 (Figs. 3 and 5) which converge toward the bed. These serve to guide and direct the two ends of the can body so as to direct them properly onto the bed 20 H. Also, there are two down pressing downwardly inclined resilient guides 7 and 8 bearing upon the top side of the can body. The rear guide 7 bears upon the upper side of the can body at its rear end. As shown 25 in Figs. 3 and 5 this guide is of sheet metal and it extends from the feed table across and above the bed H and below the clamp. This resilient guide 7 is back of the bearing rib m of the clamp, as shown in Fig. 10. 30 Accordingly when the clamp descends this down pressing resilient guide is not encountered since it occupies the recess in the bottom of the clamp between rib m and the foot 7. This guide 7 bears upon the rear 35 of the can body during the feeding of the can bottom thereinto, and it contributes in maintaining the rear end of the can body in place. The second down bearing resilient guide 8 extends partially over the bed and 40 beneath the clamp, as shown in Fig. 5, and its bearing end is located in front of the rib m so that it bears upon the front end of the can body as it is fed into place.

In inserting a can body, the workman 45 places the flat side upon the feed table and pushes it into place between the end guides 6 and beneath the down bearing top side guides 7 and 8. If there is a bottomed can on the bed plate, the can body, as it is 50 pushed in, encounters the bottomed can and forces it sidewise off the bed plate, the spring controlled door J swinging upwardly to permit the bottomed can to be discharged, as indicated in dotted lines in Fig. 6. The 55 bottomed can having been ejected, the door J swings back to its normal vertical position and serves as a stop for the leading edge of the can body and pushes the can body back into place if the workman has 60 thrust it in too far.

65 *Can bottom feed table.*—There is a feed table 9 for the can bottoms located forward of the feeder and extending beyond the discharge side of the clamp, as shown in Fig. 3. The upper horizontal surface of this feed

table is above the level of the top edge of the feeder when such feeder is in its normal position of rest as shown in Fig. 1. The feed table has a downwardly inclined chute 10 extending in close proximity to the upper edge 70 of the idle feeder. The workman with one hand slides a can bottom along the feed table down the chute onto the feeder.

The frame 1 supporting the operative parts of the machine can be conveniently 75 supported upon a stand. As shown in the drawings, it is secured to stand 11 by bolts 12 passing through flanges 13 of the frame 1.

I claim—

1. A can bottoming machine having, in 80 combination, a frame; a horizontal bed adapted to receive a can body resting on its side; a vertical thrust abutment above the bed against which the top edge of the can body is thrust; a feed table carrying guides 85 for said can body as it is inserted into position upon said bed; a normally raised can body clamp pivoted to said frame which overlies said bed; a stop to limit the downward movement of said clamp; an actuating 90 pedal pivoted to said frame; a bell crank lever pivoted to said frame, one arm of which extends beneath and normally upholds said clamp; a link connecting the other end of said lever to said pedal which 95 controls the movement of said lever to permit the lowering of said clamp until it encounters said stop; a toggle arm on said pedal; a swinging can bottom feeder having 100 a die to receive a can bottom of similar contour to the end of the can body; a toggle link connecting the can bottom feeder to said toggle arm, whereby said pedal rocks said feeder toward the can body to unite said bottom and body as said clamp lowers, the 105 feeding movement of the feeder being completed after the clamp is at rest; and a spring returning all of the movable parts to their normal positions.

2. A can bottoming machine having, in 110 combination, a frame; a horizontal bed adapted to receive a can body resting on its side; a vertical thrust abutment above the bed against which the top edge of the can body is thrust; a normally raised pivoted 115 can body clamp which overlies said bed; a stop to limit the downward movement of said clamp; an actuating pedal pivoted to said frame; a bell crank lever pivoted to said frame, one arm of which extends beneath and normally upholds said clamp; a link connecting said lever to the pedal which 120 controls the movement of said lever to permit the lowering of said clamp until it encounters said stop; a toggle arm on said pedal; a swinging can bottom feeder having a die to receive a can bottom of similar contour to the end of the can body; a toggle link connecting the can bottom feeder to 125 said toggle arm whereby said pedal rocks 130 said feeder toward the can body to unite said bottom and body as said clamp lowers, the feeding movement of the feeder being completed after the clamp is at rest; and a spring returning all of the movable parts to their normal positions.

the can bottom feeder toward the can body to unite said bottom and body as said clamp lowers, the feeding movement of the feeder being completed after the clamp is at rest; 5 and a spring returning all of the movable parts to their normal positions.

3. A can bottoming machine having, in combination, a horizontal bed adapted to receive a can body resting on its side; a 10 vertical thrust abutment above the bed against which the top edge of the can body is thrust; a normally raised swinging can body clamp which overlies said bed; a stop to limit the downward movement of said 15 clamp; a lever, one arm of which extends beneath and normally upholds said clamp; a can bottom feeder constructed to receive a can bottom of similar contour to the end of the can body; an actuator operatively connected to said lever and to said can bottom 20 feeder whereby as said clamp lowers said feeder is moved toward the can body to unite said bottom and body, the movement of the feeder being completed after the clamp is 25 at rest; and a spring returning all of the movable parts to their normal positions.

4. A can bottoming machine having, in combination, a horizontal bed adapted to receive a can body resting on its side; a vertical thrust abutment above the bed against which the top edge of the can body is thrust; a normally raised movable can body clamp which overlies said bed; a lever which extends beneath and normally upholds said 30 clamp; a movable can bottom feeder constructed to receive a can bottom of similar contour to the end of the can body; and a common actuator for the can body clamp and for the can bottom feeder acting to move 35 the feeder toward the can body to unite said bottom and body as the clamp lowers, the feeding movement of the feeder being completed after the clamp is at rest.

5. A can bottoming machine having, in combination, a bed adapted to receive a can body; a thrust abutment at right angles to the bed against which the top edge of the can body is thrust; a movable can body clamp opposite said bed; a movable can bottom 40 feeder constructed to receive a can bottom of similar contour to the end of the can body; and a common actuator operatively connected to the clamp and to the feeder and acting first to bring the clamp into position 45 to confine the can body and then to force the can bottom held by the feeder upon the can body.

6. A can bottoming machine having, in combination, a frame, a bed H to accommodate a flat round ended can body, said bed having a groove j near the rear thereof; an upwardly extending stop k at the rear of said bed, with a steel thrust abutment I secured thereto; a feed table 2 attached to said 50 frame in the same plane as said bed, carry-

ing inwardly converging end guides 6, 6, and resilient top guides 7, 8, for the ends and top side of said can body as it is inserted upon said bed; a normally raised weighted can body clamp G pivoted to the rear of 70 said frame and overlying said bed; a depending foot l, on the under surface of said clamp which engages said stop k, to limit the downward movement of said clamp; a depending rib m on the bottom of said 75 clamp which engages said can body at its middle when it is on said bed; side guides K, K, on said clamp alongside the foot l; a flange n at the front of said clamp shaped to fit said can body; a depending finger p, 80 on the inlet side of said clamp alongside said rib m to aid in centering the can body beneath said clamp; and a spring controlled door J on said clamp at its discharge side functioning as a stop for an inserted can 85 body but yielding to permit the discharge of a bottomed can.

7. A can bottoming machine having, in combination, a bed to accommodate a flat round ended can body; an upwardly extending thrust abutment at one end of the bed; a normally raised movable can body clamp above said bed; a depending crosswise extending can body engaging rib on the under surface of said clamp; a flange at the front 90 of said clamp to fit said can body; a depending can centering finger on the inlet side of said clamp; and a spring controlled door on said clamp at its discharge side functioning as a stop for an inserted can body but yielding to permit the discharge of a bottomed 95 can.

8. A can bottoming machine having, in combination, a bed to accommodate a flat round ended can body; a normally raised 100 movable can body clamp overlying said bed; a depending crosswise extending can body engaging rib on the under surface of said clamp; a stop limiting the downward movement of said clamp; and a flange at the 110 front of said clamp shaped to fit said can body.

9. A can bottoming machine having, in combination, a bed to accommodate a flat round ended can body; a movable clamp 115 which confines and positions a can body on the bed; and a spring controlled door at the discharge side of the clamp functioning as a stop for an inserted can body but yielding to permit the discharge of a bottomed can. 120

10. A can bottoming machine having, in combination, a bed to accommodate a flat round ended can body, a movable can body clamp overlying the bed and having a depending rib at its middle to bear upon the 125 upper side of the can body when the clamp lowers; a feed table at one side of the bed having two converging guides for the respective ends of the can body, a resilient down pressing guide extending across and 130

above the bed below the clamp and at the rear of said depending rib and adapted to bear upon the upper side of the can body near the rear end thereof, and a second down pressing resilient guide extending partly over the bed beneath the clamp and in front of said depending rib and adapted to bear upon the upper side of the can body near its front end.

10 11. A can bottoming machine having, in combination, a bed to accommodate a flat round ended can body; a movable can body clamp overlying the bed; a feed table at one side of the bed having two converging guides 15 for the respective ends of the can body and a resilient down pressing guide extending across and above the bed and beneath the clamp and adapted to bear upon the upper side of the can body.

20 12. A can bottoming machine having, in combination, a bed to accommodate a flat round ended can body; a movable can body clamp overlying the bed and having a depending rib at its middle to bear upon the 25 upper side of the can body when the clamp lowers; a feed table at one side of the bed having a resilient down pressing guide extending across and above the bed and beneath the clamp at the rear of said depending rib and adapted to bear upon the upper 30 side of the can body near the rear end thereof, and a second down pressing resilient guide extending partly over the bed and beneath the clamp in front of said depending rib and adapted to bear upon the top 35 side of the can body near its front end.

13. A can bottoming machine having, in combination, a bed to accommodate a flat round ended can body; a movable can body 40 clamp overlying said bed; and a feed table alongside the bed and clamp having inwardly converging side guides for the ends of the can bodies and resilient top guides bearing upon the upper side of the can body 45 as it is slid into place beneath the clamp.

14. A can bottoming machine having, in combination, a bed to accommodate a can body; a clamp for said can body; a can bottom feeder movable toward and from 50 the front end of the can body held by said clamp, said feeder having a can bottom die to receive and position a recessed can bottom, and upwardly flared converging outer ends; a feed table for the can bottoms; and 55 a downwardly inclined chute leading from said feed table to said feeder.

15. A can bottoming machine having, in combination, a bed to accommodate a can body; a clamp for said can body; and a can 60 bottom feeder movable toward and from the

front end of the can body held by said clamp, said feeder having a can bottom die to receive and position a recessed can bottom, and upwardly flared converging outer ends.

65

16. A can bottoming machine having, in combination, a bed to receive a can body; a vertically movable can body clamp overlying said bed; a support normally holding the clamp in its uplifted position; a movable can bottom feeder at the front of said bed; and a common actuator for said feeder and clamp support operatively connected therewith to move the feeder toward the can body and to withdraw the clamp support so that the clamp lowers by gravity upon the can body on the bed.

70

17. A can bottoming machine having, in combination, a stationary flat bed to receive and accommodate a flat round ended can body lying on its side; a thrust abutment projecting from said bed against which the rear end of the can body is thrust; a movable can body clamp overlying said bed; and a can bottom feeder to carry a can bottom movable toward the front end of the can body held by said can body clamp thereby forcing the can bottom carried by the feeder into the can body, said feeder having a can bottom die which fits the recess in a recessed can bottom placed thereon by hand and positions the can bottom as it is fed by the feeder to the can body.

80

18. A can bottoming machine having, in combination, a stationary flat bed to receive and accommodate a flat round ended can body lying on its side, a thrust abutment projecting from said bed against which the rear end of the can body is thrust; a movable can body clamp overlying said bed; and a can bottom feeder on which can bottoms are placed by hand, said feeder being movable toward the front end of the can body held by said can clamp thereby forcing the can bottom carried by the feeder into the can body.

85

19. A can bottoming machine having, in combination, a bed to receive and accommodate a can body lying on its side; a thrust abutment against which the rear end of the can body is thrust; a movable can body clamp overlying said bed; and a can bottom feeder which receives and holds a can bottom placed on it by hand, said feeder being movable toward the front end of the clamped can body thereby forcing the can bottom carried by the feeder upon the can body.

90

In witness whereof, I have hereunto signed my name.

CHARLES V. STRICKLAND.
